(57) **CLAIM**

The ornamental design for a game controller, as shown and described.

DESCRIPTION

FIG. 1 is a top, right perspective view of a game controller; FIG. 2 is a bottom, left perspective view thereof; FIG. 3 is a top view thereof; FIG. 4 is a bottom view thereof; FIG. 5 is a left-side view thereof; FIG. 6 is a right-side view thereof; FIG. 7 is a front view thereof; FIG. 8 is a back view thereof; and, FIG. 9 is an enlarged view of the circle labeled "FIG. 9" in FIG. 8. The raised features represent a stippled texture which is understood to be distributed uniformly over the surface of the claimed design upon which the texture occurs.

The even length broken lines depict portions of the game controller that form no part of the claimed design. The dash-dot broken lines illustrate bounds of the magnified portions and form no part of the claim.
